UNITED STATES PATENT OFFICE.

DAVID CLEGG, OF PHILADELPHIA, PENNSYLVANIA.

SMOKE-CONSUMING FURNACE.

SPECIFICATION forming part of Letters Patent No. 415,959, dated November 26, 1889.

Application filed August 29, 1889. Serial No. 322,326. (No model.)

To all whom it may concern:

Be it known that I, DAVID CLEGG, a citizen of the United States, and a resident of Philadelphia, Pennsylvania, have invented a 5 Smoke-Consuming Furnace, of which the following is a specification.

The object of my invention is to construct devices for attachment to locomotives, by which the smoke and cinders are carried from 10 the stack into the ash-pit and there consumed.

In the accompanying drawings, Figure 1 is a longitudinal section of sufficient of a locomotive to illustrate my invention. Fig. 2 is a transverse section through the smoke-stack 15 on the line 1 2, Fig. 1. Fig. 3 is a transverse section on the line 3 4, Fig. 1. Figs. 4 and 5 are sections of the smoke-stack on the line 5 6, Fig. 2, showing the draft-regulator in different positions. Fig. 6 is a perspective view of the 20 upper portion of the stack. Fig. 7 is a section of the stack on the line 7 8, Fig. 1; and Fig. 8 is a view of a modified form of stack.

A is the boiler of the locomotive; B, the combustion-chamber; C, the ash-pit, and b the 25 grate.

D is the smoke-box, having the usual exhaust-nozzles from the cylinders, and E is the stack. The stack in the present instance is of the peculiar form shown in Figs. 1 and 2, 30 and is provided with three passage-ways e e' e''. The central passage-way e communicates with the smoke-box D at the bottom and communicates with the downflues e' e'' at the top. A hood F is placed over the upper ends of 35 the flues and has dividing-plates f f', which pass down each of the flues, so that the smoke and cinders from the combustion-chamber pass up the central flue and are guided down the outer flues e' e'' by the hood F. The side 40 flues communicate with a longitudinal flue E' through passages E'', one at each side of the smoke-box. The passage E' extends to and communicates with the ash-pit, as shown in Fig. 1, so that any smoke or cinders that 45 pass through the passages e, e', and E' are directed into the ash-pit, the larger cinders falling to the bottom of the ash-pit, while the smoke and lighter cinders pass through the fuel on the grate b and are consumed.

50 In order to create sufficient draft to carry

the cinders and smoke into the ash-pit, I provide a funnel-shaped head G, situated at the upper end of the smoke-stack. This head has a flaring mouth g, and is preferably provided with a screen g'. On the upper portion 55 of the head is an opening h, provided with a valve II, hinged at h'. This valve has an arm h'', which is connected, through the medium of rods i and a bell-crank lever i', with a hand-lever I in the cab of the engine, so 60 that when the locomotive is standing—as, for instance, at a station—the engineer can raise the valve II and permit the smoke to pass out of the stack. As soon as the engine pulls out from the station the engineer reverses the 65 lever I, thus closing the valve II, so that air passes through the head G and into the side 70 passages e' e'', thus causing a forced draft and forcing the cinders and smoke into the ash-pit.

To increase the draft where circumstances require, I cut an opening a in the front of each side passage e' e'' and insert in the opening pivoted slats a', connected after the manner of a window-blind, one of the slats having an arm a'' linked to a lever a'', which in turn is connected to the rod i, so that when the valve II is closed, as shown in Fig. 4, the slats cause the air to pass downward into the side flues e' e'', and thus add to the force of 75 80 the draft in carrying the cinders and smoke to the ash-pit; but when the valve is raised to the position shown in Fig. 5 the slats are reversed and the air is permitted to pass upward into the side flues e' e'', thus aiding in 85 carrying the smoke out through the top of the stack. These slats can be worked independently of the valve II, if desired, so that they can be closed when it is required to cut off the air through the openings a.

In the modification shown in Fig. 8, instead of the down passages being at the sides of the central passage e, said down passages are in front and rear of the central passage, and in this case only the front down passage is provided with slats.

I claim as my invention—

1. The combination of the combustion-chamber and ash-pit with the smoke-stack open at its upper end and having communi- 95 100

cating up and down flues with a deflecting-hood, and a valved inlet-opening in the down-flue, substantially as described.

2. The combination of the smoke-stack provided with up and down flues, the deflecting-hood, the head having an air-inlet opening communicating with the downflues, and a valved opening in the upper portion of said head, and mechanism for operating the valve from the cab of the engine, substantially as described.

3. The combination of the smoke-stack having up and down flues with openings in said downflues, and slats in each of said openings for directing air into the stack and creating a draft in the downflues for carrying the smoke to the ash-pit, substantially as described.

4. The combination of the stack having up and down flues, openings in said downflues

with pivoted slats in said openings, said slats being controlled from the cab of the engine, so as to regulate the draft, substantially as described.

5. The combination of the smoke-stack, the up and down flues therein, a valved opening in the top of said stack, and openings in the downflues with pivoted slats therein, a rod connected to the slats and to the valve-rod, said rod being connected to a lever in the cab, so that on the operation of said lever the slats and valve will be operated simultaneously, substantially as described.

In testimony whereof I have signed my name to this specification in the presence of two subscribing witnesses.

DAVID CLEGG.
